Primary Examiner — Darcey E Gottschalk*Assistant Examiner* — Vanessa M. Pursley(74) *Attorney, Agent, or Firm* — Collard & Roe, P.C.(57) **CLAIM**

The ornamental design for a carton blank for a bottle cap, as shown and described.

DESCRIPTION

FIG. 1 is a front view of a carton blank for a bottle cap, showing our new design in a partially assembled position; FIG. 2 is a rear view thereof; and, FIG. 3 is a front, left side and bottom perspective view thereof.

The features shown in broken lines depict portions of the carton blank for a bottle cap that form no part of the claimed design.
